(57) **CLAIM**

The ornamental design for a backpack with light, substantially as shown and described.

DESCRIPTION

FIG. 1 is a top, front perspective view of the backpack with light.

FIG. 2 is a front elevational view of the design of FIG. 1.

FIG. 3 is a left elevational view of the design of FIG. 1.

FIG. 4 is a right elevational view of the design of FIG. 1.

FIG. 5 is a rear elevational view of the design of FIG. 1.

FIG. 6 is a top view of the design of FIG. 1.

FIG. 7 is a bottom view of the design of FIG. 1.

FIG. 8 is an enlarged view of the light patch shown in FIG. 1, with the lights in an “off” condition; and,

FIG. 9 is an enlarged view of the light patch shown in FIG. 1, with the lights in an “on” condition.

The portions of the figures shown in broken lines represent features that do not form part of the claimed design.

1 Claim, 9 Drawing Sheets
